(57) **CLAIM**

The ornamental design for a home networking device, as shown.

DESCRIPTION

FIG. 1 is a perspective view of a first embodiment of a home networking device.

FIG. 2 is a bottom view of the first embodiment of the home networking device.

FIG. 3 is a top view of the first embodiment of the home networking device.

FIG. 4 is a front view of the first embodiment of the home networking device.

FIG. 5 is a back view of the first embodiment of the home networking device.

FIG. 6 is a right side view of the first embodiment of the home networking device.

FIG. 7 is a left side view of the first embodiment of the home networking device.

FIG. 8 is a perspective view of the second embodiment of the home networking device.

FIG. 9 is a bottom view of the second embodiment of the home networking device.

FIG. 10 is a top view of the second embodiment of the home networking device.

FIG. 11 is a front view of the second embodiment of the home networking device.

FIG. 12 is a back view of the second embodiment of the home networking device.

FIG. 13 is a right side view of the second embodiment of the home networking device.

FIG. 14 is a left side view of the second embodiment of the home networking device.

FIG. 15 is a perspective view of a third embodiment of the home networking device; and,

FIG. 16 is a perspective view of a fourth embodiment of the home networking device.
